(57) **CLAIM**

The ornamental design for a fishing lure, as shown and described.

DESCRIPTION

FIG. 1 is a perspective view of the fishing lure showing my new design;

FIG. 2 is a front view thereof, the rear view thereof being a mirror image of the view shown;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is another perspective view of the fishing lure with the tail curled showing my new design in use.
